THE NORRIS PETERS CO., PORT ALLEGANY, WASHINGTON, D. C.

UNITED STATES PATENT OFFICE.

HENRY WANAMAKER, OF ALBANY, NEW YORK.

PUMP.

1,303,621.

Specification of Letters Patent. Patented May 13, 1919.

Application filed August 16, 1915. Serial No. 45,731.

To all whom it may concern:

Be it known that I, HENRY WANAMAKER, of Albany, in the county of Albany, and in the State of New York, have invented a certain new and useful Improvement in Pumps, and do hereby declare that the following is a full, clear, and exact description thereof.

My invention relates to pumps and has for its object to provide a simple, efficient pump adapted to discontinue its pumping operation automatically when a predetermined pressure is attained. Although applicable for many purposes, it is particularly advantageous when embodied in apparatus for inflating automobile tires, and such embodiment has been chosen for purposes of illustration.

Other and further objects of my invention will be apparent from the following description of the above-mentioned embodiment and from an inspection of the accompanying drawings, in which:

Figure 1 is a vertical, longitudinal section of a double-acting pump adapted to inflate automobile tires;

Fig. 2 a plan of the embodiment shown in Fig. 1; and

Fig. 3 a perspective of the illustrated embodiment mounted on an automobile.

Similar reference characters refer to similar parts throughout the drawings.

The embodiment illustrated in the drawings comprises a double-acting pump of any desired type having cylinders 1, pistons 2, piston rods 3, and crank shaft 4. The crank shaft may be connected to a source of power and its movement controlled in any desired manner. In the embodiment illustrated, the outer end of said crank shaft 4 has splined thereon a gear 5 provided with a circular flange 6 which extends over an extension 7 on cylinder 1, thereby forming an inclosed circular pocket in contact with the outlet of a by-pass 8 in the side wall of said cylinder

45 1. Gear 5 is adapted to engage with and be disengaged from a pinion 9 fixed to any moving part, as shaft 10. In this embodiment, gear 5 normally is held in inoperative position by an armature or latch 12 controlled by magnets or solenoids 13 adapted to be energized by the closing of a circuit 14 through the instrumentality of a button 15. The momentary closing of circuit 14 will energize said magnets or solenoids 13 55 thereby retracting latch 12 from the path of gear 5 which then will be forced into mesh

with pinion 9 by spring 11 and maintained in mesh until forced into inoperative position as hereinafter described. A handle 16 also is connected to latch 12 in order to operate the same if current should fail or if magnet or solenoid 13 should get out of order. The pump is provided with ordinary intake and outlet valves 20 and 21 respectively, the latter of which opens into a chamber 22. The ordinary outlet for chamber 22 is provided with a pipe 23 which may lead to any desired place. Said chamber 22 also is provided with an excess pressure port 24 leading into a recess or larger area 25 which communicates with by-pass 8. The port and by-pass normally are closed by a valve or piston 26 controlled by a spring 27 which may be adjusted and set by a screw 28 to suit the required maximum pressure. It will be noted that port 24 is of much less diameter than recess 25, which will cause by-pass 8 to be uncovered very quickly as soon as a predetermined pressure is attained, thereby increasing the accuracy with which the pump 80 will cease its operation at the desired predetermined pressure.

A convenient adaptation to automobiles of the tire pumping embodiment of my invention is illustrated in Fig. 3 of the drawings. 85 The pump is mounted in any convenient place in the hood adjacent to a moving shaft, as the magneto or fan shaft, on which pinion 9 may be secured. Current for circuit 14 may be obtained from any battery source 90 which may be in service; such as the starting or the lighting batteries. Pipe 23 leads to the inside of the dash, ending in a stopcock 30 adjacent to which is secured a pressure gage 31. The operation of this embodiment 95 is as follows:

To test the pressure at which the pump will discontinue its pumping operation, stopcock 30 is closed and button 15 pressed, which will lift latch 12, permitting spring 100 11 to throw gear 5 into mesh with pinion 9 which is revolving with the magneto or other shaft to which it is secured. This starts the operation of the pump, and stop-cock 30 being closed, the air will be compressed in chamber 22 and pipe 23 until the pressure is sufficient to open valve 26 against the force of its spring 27 sufficiently to uncover by-pass 8. The air then will enter the by-pass and throw gear 5 into inoperative position 105 110 where it will be held by latch 12 falling into position in the path thereof. Pressure gage

31 will have indicated the exact pressure at which the pumping operation ceases. If the pressure attained was not the desired pressure, screw 28 can be adjusted to increase or decrease the effectiveness of spring 27 and sufficient trials and adjustments had until the pump will discontinue pumping at the exact pressure desired. When this has been done the pump is ready for future service.

10 It will release automatically at the pressure to which it has been set and requires no further adjustment unless it is desired to operate at a higher or lower pressure. Furthermore, the operator need pay no attention to the gage or to the operation of the pump. It is necessary only to connect a flexible tube from stop-cock 30 to the tire which it is desired to inflate. The stop-cock is opened, button 15 pressed, and the pump will inflate

15 the tire to the pre-determined pressure and discontinue the pumping operation automatically as soon as that pressure is attained. It is not necessary for the operator to watch the pressure gage as all danger of over-inflation or under-inflation is obviated.

20

25

In order that gear 5 and pinion 9 always may mesh as soon as locking pin 12 releases gear 5 from its inoperative position, the opposite vertical edges of gear 5 and pinion 9 respectively are beveled so that a positive engagement always is assured.

Many modifications of my invention will be apparent to those skilled in the art without departing therefrom or from the scope 35 of the claims, the embodiment described being illustrative merely of many embodiments and uses.

Having described one embodiment of my invention what I claim is:

40 1. The combination of a pump, means to operate said pump comprising a mechanical connection, and means to discontinue the pumping operation when a predetermined pressure is attained comprising means to lead compressed air directly to a surface of one of the elements of said mechanical connection to disconnect the same.

45 2. The combination of a pump, means to operate said pump comprising gearing, means to discontinue the pumping operation when a predetermined pressure is attained comprising means to disconnect said gearing by air pressure applied to said gearing.

50 55 3. The combination of a pump, means to operate said pump comprising gearing, and means to discontinue the pumping operation when a predetermined pressure is attained comprising means to disconnect said gearing by the application of the attained pressure on said gearing.

55 60 65 4. The combination of a pump, means to operate said pump, and means to discontinue the pumping operation when a predetermined pressure is attained comprising a pair

of gears and a spring adapted to maintain said gears in mesh.

5. The combination of a pump, means to operate said pump, and means to discontinue the pumping operation when a predetermined pressure is attained comprising a pair of gears and means to maintain said gears normally out of mesh comprising a latch.

6. The combination of a pump, means to operate said pump, and means to discontinue the pumping operation when a predetermined pressure is attained comprising a pair of gears and means to maintain said gears normally out of mesh comprising a latch and means to operate said latch.

7. The combination of a pump, means to operate said pump, and means to discontinue the pumping operation when a predetermined pressure is attained comprising a pair of gears and means to maintain said gears normally out of mesh comprising a latch and means to operate said latch comprising a solenoid.

8. The combination of a pump, means to operate said pump, and means to discontinue the pumping operation when a predetermined pressure is attained comprising a pair of gears, a spring adapted to maintain said gears in mesh, a latch adapted normally to maintain said gears out of mesh, and means to operate said means to withdraw said latch whereby said spring will force said gears into mesh.

9. The combination of a pump, means to operate said pump, and means to discontinue the pumping operation when a predetermined pressure is attained comprising a pair of gears having teeth beveled on opposite vertical edges, one of which gears is adapted to be moved into and out of engagement with the other of said gears.

10. The combination of a pump having a chamber and a by-pass therefrom, means to operate said pump comprising gearing adjacent the exit of said by-pass, and means to discontinue the pumping operation when a predetermined pressure is attained comprising means to disconnect said gearing by pressure sent from said chamber through said by-pass to disconnect said gearing.

11. The combination of a pump, a crank shaft, means to operate said crank shaft and said pump comprising a gearing, one of said gears being secured to a rotating part and the other of said gears being splined to said crank shaft, means to force said splined gear into mesh with said rotating gear, and latching means to retain said splined gear in inoperative position.

12. The combination of a pump, a crank shaft, means to operate said crank shaft and said pump comprising a gearing, one of said gears being secured to a rotating part and the other of said gears being splined to said crank shaft, means to force said splined

gear into mesh with said rotating gear, and means to retain said splined gear in inoperative position comprising a latch.

13. The combination of a pump, a crank shaft, means to operate said crank shaft and said pump comprising a gearing, one of said gears being secured to a rotating part and the other of said gears being splined to said crank shaft, means to force said splined gear into mesh with said rotating gear, and means to retain said splined gear in inoperative position comprising a latch and means to operate said latch.

14. The combination of a pump, a crank shaft, means to operate said crank shaft and said pump comprising a gearing, one of said gears being secured to a rotating part and the other of said gears being splined to said crank shaft, means to force said splined gear into mesh with said rotating gear, and means to retain said splined gear in inoperative position comprising a latch and means to operate said latch comprising a solenoid.

15. The combination of a pump, means to operate said pump comprising a driving part and a driven part, and means to discontinue the pumping operation when a predetermined pressure is attained comprising an air pocket on a driven part adapted to receive air pressure to disconnect said part.

16. The combination of a pump, means to

operate said pump comprising a shaft, a driven part provided with an air pocket mounted on said shaft, means to discontinue the pumping operation when a predetermined pressure is attained comprising means to admit air pressure to said pocket to move said driven part to inoperative position.

17. The combination of a pump, means to operate said pump, a chamber, a port leading from said chamber, a recess connected to said port, a by-pass leading from said recess, and a spring pressed valve closely fitting said recess and adapted to close said port and overlap said by-pass when in closed position.

18. The combination of a pump, means to operate said pump, a chamber, a port leading from said chamber, a recess connected to said port, a by-pass leading from said recess, a spring pressed valve closely fitting said recess and adapted to close said port and overlap said by-pass when in closed position and means to regulate the pressure necessary to operate said spring pressed valve to open said port and uncover said by-pass.

In testimony that I claim the foregoing I have hereunto set my hand.

HENRY WANAMAKER.
